UNITED STATES PATENT OFFICE.

WILLIAM R. McCOMAS, OF OAKLEY, ASSIGNOR TO CRANE, BREED & CO., OF CINCINNATI, OHIO.

DESIGN FOR A COFFIN ORNAMENT.

SPECIFICATION forming part of Design No. 13,159, dated August 8, 1882.

Application filed June 12, 1882. Term of patent 3½ years

To all whom it may concern:

Be it known that I, WILLIAM R. McCOMAS, a citizen of the United States, residing at Oakley, county of Hamilton, and State of Ohio, 5 have invented and produced a new and original Design for an Ornament or Emblem for Burial-Cases or Coffins, of which the following is a specification, reference being had to the accompanying drawing, forming part thereof.

10 The figure in the drawing represents my newly-designed emblem or ornament.

My invention consists in the head of a cherub with flowing hair, surrounded by radiating

feathers forming conventional wings, and used as a coffin emblem or ornament.

Having thus fully described my invention, what I claim as new, and desire to secure by Letters Patent, is—

A design for an emblem or ornament for coffins herein shown and described, consisting 20 of the head of a cherub surrounded by radiating feathers, as described.

WM. R. McCOMAS.
